[57] CLAIM

The ornamental design for a combined handset telephone and cradle set, as shown and described.

DESCRIPTION

FIG. 1 is a right side perspective view of a combined handset telephone and cradle set showing my new design;

FIGS. 2, 3, 4, and 5 are respectively top plan, right side elevational, front end and rear end elevational views thereof;

FIGS. 6, 7, 8 and 9 are respectively top plan, right side elevational, front end and rear end elevational views of the cradle;

FIGS. 10, 11, 12 and 13 are respectively right side elevational, front and rear end elevational, and bottom plan views of the handset telephone.

In FIGS. 6-9, and 10-13, the components of the set are shown separately for convenience and clarity of illustration.

FIG. 1.

FIG. 2.
